UNITED STATES PATENT OFFICE

PAUL C. OSCANYAN, OF BOGOTA, NEW JERSEY; ELSIE STONE OSCANYAN AND JOHN A. H. HOPKINS EXECUTORS OF SAID PAUL C. OSCANYAN, DECEASED

FLUSHING APPARATUS

Application filed September 27, 1928. Serial No. 308,642.

This invention is an improvement in flushing apparatus, and more particularly in apparatus of the air compression tank type.

In the usual construction of flushing apparatus of the type in question, the operating parts extend through the enclosing wall housing the valve mechanism, and such parts must be packed to prevent the escape of water.

Such packings if they prevent the escape of water make the parts hard to operate, and they are very liable to deterioration.

One of the primary objects of the present invention is the provision in apparatus of the type in question, of valve mechanism wholly enclosed, and with operating mechanism outside the enclosing wall, the wall having flexible portions, in the nature of diaphragms, which are laterally movable, to enable operation of the valve mechanism.

Another object is the provision of a diaphragm operated flush valve, wherein the initial opening of the flush valve admits the full water pressure to the diaphragm to operate the same, and wherein auxiliary mechanism is provided externally operated to enable the inlet of initial pressure to unseat the flush valve.

Another object is the provision of mechanism for draining the diaphragm chamber after the flushing operation to enable seating of the flush valve, externally operated, and without direct connection with the external operating mechanism.

Another object is the provision in such apparatus, of means facilitating inspection and removal of the operating parts.

Another object is the provision of a relatively simple and relatively inexpensive apparatus capable of operation with the usual tank, or with a siphon filled tank, and adapted to be arranged within the wall of the bath-room.

With these and other objects in view the invention consists in the construction and novel combination of parts fully described hereinafter, illustrated in the accompanying drawings, and pointed out in the claims appended hereto, it being understood that various changes in the form, proportion, size

and minor details of construction within the scope of the claims, may be resorted to without departing from the spirit of the invention.

In the drawings forming a part hereof:—

Fig. 1 is a side elevation of the improved apparatus.

Fig. 2 is an enlarged detail in section of the flushing mechanism.

In the present embodiment of the invention, a valve casing 1 is provided, having an inlet 2 at one side, which is connected by a pipe 3, with a compression tank 4, the said tank being adapted to contain a definite charge of water, which during its entrance to the tank compresses the air in the top of the tank.

The top of the casing 1 is closed by a plug 5 threaded into an opening in the top, and the said plug has a handle 6 for convenience in manipulating the same. Intermediate its top and bottom the casing has a partition 7a provided with a port 7 normally closed by a valve in the form of a cup 8, having a filling 9 of packing, which rests upon the upper face of the partition 7a when the valve is in closed position.

The valve has a stem 12, which moves in a bearing 13 supported by the cap 5 before mentioned, the cap having arms 14, which are connected with the bearing. At its upper end the stem has a longitudinally extending slot 15, through which passes a pin 16, the ends of the pin being entered into openings in the reduced portion of the cap which engages with in the opening of the casing 1. Thus the valve and stem are connected to the cap with a lost motion connection, the pin limiting the movement of the valve.

A spring 17 encircles the stem between the bearing 13 and the valve 8—9, normally holding the valve to its seat, and a guide collar 18 is threaded on to the lower end of the stem below the valve, the collar fitting loosely within the port, and extending below the lower end of the stem as shown.

The lower end of the casing is provided with a lateral port, from which leads a pipe 19 to the bowl to be flushed. Water is supplied to the chamber 10 of the casing, and to

the tank 4, by means of a pipe 20 from a suitable source of supply, the pipe having a check valve 21 interposed therein, to prevent return of water to the source of supply.

5 At its lower end the valve casing 1 is enlarged laterally to provide a circular head 22, which is concavo-convex, and arranged with its concavity downward. This head forms one wall of a diaphragm chamber, the other wall being formed by a head 23, which is secured to the head 22 by threaded stems and wing nuts shown at 24.

15 A diaphragm 25 of suitable material is arranged within the chamber, the edges of the diaphragm being clamped between the abutting edges of the heads 22 and 23, and an opening or port 26 is provided between the chamber 11 of the casing and the diaphragm chamber. Normally the diaphragm lies in concavo-convex form on the inner face of the head 23, as shown in Fig. 2, and water is admitted to the chamber beneath the diaphragm when the valve 8-9 is opened, by means of a passage 27, which extends through the wall of the chamber 11, and through the wall of the head 23, a check valve 28 being provided at the inlet end of the passage. Referring to Fig. 2, it will be seen that the passage 27 extends outwardly and downwardly, then inwardly and downwardly, and then vertically upward, and that the inlet end is enlarged as shown at 29 for the check valve.

It will be apparent from the description that when the valve 8-9 begins to lift, water will flow through the passage 27, past the check 28, to the space beneath the diaphragm, and will lift the same. A rod 30 is slidably mounted in a bearing 31 in the head 22, and this rod has a head 32 resting on the diaphragm, and shaped to correspond with the concavity thereof.

The upper end of the rod extends to near the lower end of the stem 12, the arrangement being such that when the diaphragm is lifted, the valve will be lifted through the engagement of the rod 30 with the stem 12. Thus the valve 8-9 is lifted by the diaphragm, but water must be admitted to the space below the diaphragm to provide initial lifting movement of the valve before water can enter the passage 27. In order to enable an initial flow beneath the diaphragm, a passage 33 is provided leading from the chamber 10 to the portion 34 of a chamber, consisting of the said portion and a portion 35 of less diameter, the said chamber being provided in an extension 40 from the casing 1.

65 A valve seat 36 is provided between the portions of the chamber, and a valve 37 similar to the valve 8-9 cooperates with the seat, the valve moving downward to open communication between the parts 34 and 35 of the chamber, and moving upward to close the communication. The lower end of the portion 34 of the chamber is closed by a threaded

plug 38, and this plug is recessed on its inner face to receive a spring 39 which engages the lower end of the valve, acting normally to seat the same. The valve may be unseated by means of a push button 41, slidably mounted in a bearing nipple 42 in the cap 43 which is threaded onto the upper end of the extension 40. The button bears against a diaphragm 44 clamped between the cap and the end of the extension, and the valve has a stem 45 provided with a head 46 at its upper end, bearing against the diaphragm.

It will be apparent from the description that when the button 41 is depressed, the valve will be opened, enabling water to flow from the chamber 10, through the passage 33 and the portion 34 of the chamber into the portion 35. From this portion a passage 47 leads to the passage 27. 80

The operation of this part of the mechanism is as follows. In order to flush the bowl, the button 41 is depressed. This opens the valve 37, and water flows from the chamber 10 through the passage 33, the chamber 34—35, and the passage 47, into the lower end of the passage 27, lifting the diaphragm 25, and opening the valve 8—9. The opening of the valve 8—9 opens the passage 27, and water may now flow directly from the chamber 10 into the diaphragm chamber, beneath the diaphragm, and the closing of the valve 37 under the influence of the spring 39 is no longer material to the operation of supplying water to the space beneath the diaphragm. When the valve 8—9 is lifted, the water flows from the tank 4, through the pipe 19, to the bowl, thoroughly flushing the same.

The diaphragm chamber, that is, that portion of the same below the diaphragm is enabled to drain through a passage 48 into the chamber 11. The rate of the flow through the passage 48 is regulated by a needle valve 49, which may be adjusted by a handled screw 50. The needle valve is in a nipple 51 extending downwardly from the head 22, and the outer end of the nipple is closed by a cap 52, having a threaded opening through which the screw 50 extends. 105 110

A diaphragm 53 is clamped between the cap and the end of the nipple, and the lower end of the needle valve rests on the diaphragm. By turning the handled screw 50 in the proper direction, the extent of opening of the needle valve may be adjusted. In Fig. 1, the apparatus is shown arranged within the wall of a bathroom, for instance, so that the tank and the other mechanism is concealed. In order to enable operation of the push button 41 outside the wall, a panel opening is provided, normally closed by a panel 55. 120 125

A bracket 56 is secured to the inner face of the panel, and an elbow lever composed of arms 57 and 58 is pivoted to the bracket. One of the arms, 57 in the present instance, 120

rests upon the push button 41. The other arm 58 has an extension 59 passing through an opening in the panel, and provided with a button 60. When it is desired to flush the bowl, the button 60 is pressed inwardly. This presses the button 41 downward, and initiates the flow of the water beneath the diaphragm 25.

The opening 26 is a vent opening. It will be apparent that the tank 4 might be supplied with water by means of a siphon, if desired, instead of directly through the casing 1. Where the water contains grit, such as sand, it is advisable to apply a rubber sleeve over the bearing 31, the sleeve engaging the bearing at one end, and the rod 30 at the other. This will prevent the entrance of grit into the diaphragm chamber. In some cases it will be advisable to place a spring above the check 28. The entire mechanism is enclosed, no part thereof extending beyond the casing 1 and its associated parts.

The valve 37 is operated through the diaphragm 44, so that none of the connecting parts of the valve extend through the casing. This is true also of the adjusting mechanism for the needle valve. Water pressure is relied upon to open the flush valve. An observation opening is provided, indicated at 60. This is closed by a disk 61 of glass.

It will be apparent from the description and drawings, that the discharge is automatically held open until the pressure in the tank reaches atmospheric, that is, until the tank is entirely empty. As long as there is water in the tank the diaphragm chamber does not drain, and it commences to drain when the tank is empty. The static head beneath the diaphragm is sufficient to hold the diaphragm lifted until the chamber 10 is empty, and the tension of the spring 17 exceeds the pressure below the valve.

When the water begins to flow from the compression tank, the pressure gradually decreases, and near the end there is a low pressure, or a slight partial vacuum. In order to compensate for this, and to insure emptying of the tank, a pipe 70 extends from the top of the compression tank to the top of chamber 11. With this arrangement, the entire contents of the tank are always discharged. The pipe 70 is provided with the usual check valve 71 to retain the pressure in the tank when it is filling.

What is claimed as new is:—

1. In flushing apparatus, the combination with a source of water under pressure, of a valve normally held closed by the pressure, a diaphragm for opening the valve, manually operated means to admit pressure from above the valve to the diaphragm to provide an initial opening movement of the valve, and a pressure transmitting passage normally closed by the valve and opened by the

initial lifting movement thereof to supplement the pressure on the diaphragm.

2. In flushing apparatus, the combination with a source of water under pressure, of a valve normally held closed by the pressure, 70 a diaphragm for opening the valve, manually operated means to admit pressure from above the valve to the diaphragm to provide an initial opening movement of the valve, a pressure transmitting passage normally closed by the valve and opened by the initial lifting movement thereof to supplement the pressure on the diaphragm, and a spring for initiating the closing movement of the valve.

3. In flushing apparatus, the combination with a source of water under pressure, of a valve normally held closed by the pressure, a diaphragm for opening the valve, a passage for transmitting pressure to the diaphragm, a valve normally operative to close the passage, manually operated means to open the valve, and a supplemental passage normally closed by the first named valve and opened by the initial opening movement thereof.

4. In flushing apparatus, the combination with a source of water under pressure, of a valve normally held closed by the pressure, a diaphragm for opening the valve, manually operated means to admit pressure from above the valve to the diaphragm to provide an initial opening movement of the valve, and a pressure transmitting passage normally closed by the valve and opened by the initial lifting movement thereof to supplement the pressure on the diaphragm, the pressure transmitting passages having a common outlet to the diaphragm, and a check valve in the outlet.

5. In flushing apparatus, the combination with a source of water under pressure, of a valve normally held closed by the pressure, a diaphragm for opening the valve, manually operated means to admit pressure from above the valve to the diaphragm to provide an initial opening movement of the valve, a pressure transmitting passage normally closed by the valve and opened by the initial lifting movement thereof to supplement the pressure on the diaphragm, and a valve controlled drain passage leading from the diaphragm.

6. In flushing apparatus, the combination with a source of water under pressure, of a flushing valve normally held closed by the pressure, a diaphragm for opening the flushing valve, a plurality of passages for transmitting pressure to the diaphragm, one of said passages being normally closed by the flushing valve, a valve controlling the other passage, a casing for the diaphragm and the flushing valve, said casing having a flexible portion in its wall at the last named valve,

and operating means for the valve outside the casing, engaging the flexible portion.

7. In flushing apparatus, the combination with a source of water under pressure, of a flushing valve normally held closed by the pressure, a diaphragm for opening the flushing valve, a plurality of passages for transmitting pressure to the diaphragm, one of said passages being normally closed by the flushing valve, a valve controlling the other passage, a casing for the diaphragm and the flushing valve, a drain passage leading from the diaphragm, a valve for regulating the capacity thereof, said casing having flexible portions in its wall at the last named valves, and operating means for the valves outside of the casing engaging said flexible portions.

8. In flushing apparatus, the combination with a source of water under pressure, of a flushing valve normally held closed by the pressure, a diaphragm for opening the flushing valve, a plurality of passages for transmitting pressure to the diaphragm, one of said passages being normally closed by the flushing valve, a valve controlling the other passage, a casing for the diaphragm and the flushing valve, a drain passage leading from the diaphragm, a valve for regulating the capacity thereof, a diaphragm within the casing wall at the last named valves for moving said valves, and means outside the casing and engaging the diaphragms for moving the same.

9. In flushing apparatus, the combination with a source of water under pressure, of a valve normally held closed by the pressure, a diaphragm for opening the valve, manually operated means to admit pressure from above the valve to the diaphragm to provide an initial opening movement of the valve, and a pressure transmitting passage normally closed by the valve and opened by the initial lifting movement thereof to supplement the pressure on the diaphragm, the source of water under pressure including an air compression tank.

10. In flushing apparatus, the combination with a source of water under pressure, a flushing valve normally held closed by the pressure, a casing enclosing the valve and the diaphragm, a passage for transmitting the pressure to the diaphragm to open the valve, a normally operative valve controlling the passage, said valve having a stem, the casing wall being provided with a diaphragm against which the stem bears, and means outside the diaphragm for moving the same.

11. In flushing apparatus, the combination with a source of water under pressure, a flushing valve normally held closed by the pressure, a plurality of passages for transmitting the pressure to the diaphragm to open the valve, one of said passages being normally

closed by the flushing valve, and a normally operative manually operated valve for closing the other.

12. In flushing apparatus, the combination with a source of water under pressure, a flushing valve normally held closed by the pressure, a plurality of passages for transmitting the pressure to the diaphragm to open the valve, one of said passages being normally closed by the flushing valve, and a normally operative manually operated valve for closing the other, the source of water pressure including an air compression tank.

13. In flushing apparatus, a flushing valve including a casing having a ported partition, a valve on one side of the partition fitting against the same and adapted to be closed upon the port by the pressure, a plug having threaded engagement with the adjacent end of the casing, the valve having a stem connected to the plug by a lost motion connection, the plug being of greater diameter than the valve.

14. In flushing apparatus, a flushing valve including a casing having a ported partition, a valve on one side of the partition fitting against the same and adapted to be closed upon the port by the pressure, a plug having threaded engagement with the adjacent end of the casing, the valve having a stem connected to the plug by a lost motion connection, the plug being of greater diameter than the valve and carrying a bearing for the stem, and a spring between the bearing and the valve.

15. In flushing apparatus, a flushing valve including a casing having a ported partition, a valve on one side of the partition fitting against the same and adapted to be closed upon the port by the pressure, a plug having threaded engagement with the adjacent end of the casing, the valve having a stem connected to the plug by a lost motion connection, the plug being of greater diameter than the valve, the valve having an axially recessed extension passing through the partition, and a diaphragm for operating the valve, said diaphragm having a stem seated within the recess, whereby to open the valve when the diaphragm is moved in one direction.

16. In flushing apparatus, a flushing valve including a casing having a ported partition, a valve on one side of the partition fitting against the same and adapted to be closed upon the port by the pressure, a plug having threaded engagement with the adjacent end of the casing, the valve having a stem connected to the plug by a lost motion connection, the plug being of greater diameter than the valve, the valve having an axially recessed extension passing through the partition, a diaphragm for operating the valve, said diaphragm having a stem seated within the recess, whereby to open the valve when the diaphragm is moved in one direction, a plurality of passages leading from the valve side

of the partition to the opposite side of the diaphragm, one of the said passages being normally closed by the flushing valve, and a releasable valve for closing the other.

17. In flushing apparatus, the combination with a source of water under pressure, of an air compression tank, a valve for closing the tank normally held closed by the pressure therein, a diaphragm for opening the valve, and a by-pass from the tank to the valve chamber for holding the valve open until the tank is empty.

18. In flushing apparatus, the combination with a source of water under pressure, of an air compression tank, a valve for closing the tank normally held closed by the pressure therein, a diaphragm for opening the valve, a plurality of by-passes from the tank to the diaphragm, releasable means normally closing one of the by-passes, the other being closed by the valve whereby to maintain pressure on the diaphragm to hold the valve open until the chamber is emptied.

19. In flushing apparatus, the combination with a source of water under pressure, of an air compression tank, a valve for closing the tank normally held closed by the pressure therein, a diaphragm for opening the valve, a plurality of by-passes from the tank to the diaphragm, releasable means normally closing one of the by-passes, the other being closed by the valve whereby to maintain pressure on the diaphragm to hold the valve open until the chamber is emptied, and means to bleed the diaphragm chamber.

20. In flushing apparatus, the combination with a source of water under pressure, of a valve normally held closed by the pressure, pressure operated means for opening the valve, manually operated means to admit pressure to said means to provide an initial opening movement thereof, and a pressure transmitting passage normally closed by the valve and opened by the initial lifting movement thereof to supplement the pressure admitted by said first named means.

21. In flushing apparatus, the combination with a source of water under pressure, a flushing valve normally held closed by the pressure, a plurality of passages for transmitting the pressure to the other side of the valve to open the same, one of said passages being normally closed by the valve, and a manually operated valve controlling the other passage.

22. In flushing apparatus, a flushing valve including a casing having a ported partition, a valve on one side of the partition fitting against the same and adapted to be closed upon the port by the pressure, pressure operated means for opening the valve, a chamber for said means having one wall constituted by the casing and another wall detachably connected with the casing to enable access to said means without removal of the valve, said means having a pin extending through the

casing wall and contacting with the valve to open the valve when said means is moved in one direction.

23. In flushing apparatus, the combination with a source of water under pressure, of a valve positioned to be normally held closed by the water pressure, means operated by water under pressure from the source to open the valve, a passage leading from the source to said means to transmit water from the source to operate the same, said passage being normally closed by the valve, and manually operated means to provide an initial opening of the valve whereby to open said passage.

24. In flushing apparatus, a flushing valve including a casing having a ported partition, a valve on one side of the partition fitting against the same and adapted to be closed upon the port by the pressure, pressure operated means for opening the valve, a chamber for said means having one wall constituted by the casing and another wall detachably connected with the casing to enable access to said means without removal of the valve, said means having a pin extending through the casing wall and contacting with the valve to open the valve when said means is moved in one direction, said casing having an opening closed with a transparent plate for enabling observation of the valve.

Signed at New York city, in the county of New York and State of New York this 19th day of September, A. D. 1928.
